G. M. MERWIN.
DELIVERY PIPE FOR FODDER CUTTERS.
APPLICATION FILED NOV. 4, 1912.

1,241,540.

Patented Oct. 2, 1917.

UNITED STATES PATENT OFFICE.

GEORGE M. MERWIN, OF BERWYN, ILLINOIS, ASSIGNOR TO INTERNATIONAL HARVESTER COMPANY OF NEW JERSEY, A CORPORATION OF NEW JERSEY.

DELIVERY-PIPE FOR FODDER-CUTTERS.

1,241,540.

Specification of Letters Patent.

Patented Oct. 2, 1917.

Application filed November 4, 1912. Serial No. 729,366.

To all whom it may concern:

Be it known that I, GEORGE M. MERWIN, a citizen of the United States, residing at Berwyn, in the county of Cook and State 5 of Illinois, have invented certain new and useful Improvements in Delivery-Pipes for Fodder-Cutters, of which the following is a specification.

My invention relates to delivery pipes in 10 general as used in connection with pneumatic mechanism for conveying straw, chaff or other material, such as ensilage, from a machine into a silo or other receptacle, and in particular to the construction of the delivery end of the conveyer pipe whereby it 15 may be adjusted in a manner to deflect the material in a desired direction; the object of my invention being to provide a construction that may be readily manipulated for the 20 required purpose, comprising few parts, strong and durable and efficient in operation.

In order that my invention may be clearly 25 and fully disclosed, I have illustrated in the accompanying drawings one embodiment which it may assume in practice, although my invention is not limited to this embodiment and may appear in modified form.

In these drawings:

30 Figure 1 represents a side elevation of the delivery end of a conveyer pipe having my invention embodied in its construction;

Fig. 2 is a cross section of Fig. 1 along line A—B;

35 Fig. 3 is a plan view of a bracket sheave mechanism forming part of the pipe adjusting means;

Fig. 4 is a side elevation of Fig. 3;

40 Fig. 5 represents an end view of part of the bracket member as shown in Figs. 3 and 4.

The same reference numerals designate like parts throughout the several views.

1 represents the body of the pipe that may 45 be attached to a fan casing in any of the well known ways, and is provided with a flanged member 2 that is secured to the upper end thereof. 3 represents the delivery end of the pipe, having a flanged member 4 secured to the lower end thereof that is connected 50 with the flanged member 2 by means of clips 5 in a manner permitting the delivery section to turn about the axis of the body section, and 6 represents a clamping

member operative to secure the parts in any 55 position of adjustment.

The delivery portion of the pipe comprises two curved upper deflector and lower delivery pipe sections 7 and 8, respectively, having their adjacent inner ends connected 60 by means of a hinge mechanism 9 whereby the upper section may be adjusted in a manner to deflect the material in various directions. The curved portions of the deflector and the delivery pipe sections are open along 65 their inner sides, forming a curved channel along which the material flows under the force of the air blast; the curved ensilage deflecting surface and the member 8 preferably being disposed in a single arc struck 70 from a common point and of slightly smaller radius than that of the surface of the member 7. It will also be noted that the deflecting surface of the member 8 is of such a length as to deflect the ensilage through 75 slightly more than a right angle, the ensilage thereby being directed slightly downward before it passes into the coöperating deflecting member 7.

The hinge mechanism 9 includes bracket 80 members 10 having the legs 11 thereof secured to opposite sides of the movable section 7 of the delivery end of the pipe, and the bolt 12 connects the parts in hinged relation. The bracket members 10 are provided with vertically arranged arms 13, spaced apart laterally to receive between them one end of a brace member 14, having the opposite end thereof secured to the movable section 7. 15 represents a bracket member 90 secured to the upper side of member 8 of the delivery pipe, and carrying a sheave 16 that is provided with a threaded axial opening that receives the horizontally disposed end of a rod 17, bent upward and laterally 95 at different points intermediate its ends, the opposite end of the rod being secured to the upper ends of the bracket members 10. The sheave member 16 operates as an adjusting nut in controlling the position of the rod 17 100 and the adjustable section 7, and a rope 18 is received by the sheave in a manner whereby the operator may adjust the section 7 from the ground as desired.

In the operation of the device the ensilage 105 is, of course, forced up through the delivery end 3 of the pipe by the blower of the ensilage cutter. As it moves forward it is de-

flected outward and slightly downward by the curved deflecting surface of the member 8 in such a manner as always to be delivered at the proper angle to the adjustable deflector 7, which then deflects it in such a manner as to spread it within the silo or upon the pile. When it is desired to adjust the deflector 7, this is readily accomplished by pulling on the rope 18 in the desired direction, thereby causing the rod 17 to be fed longitudinally of the member 8 in such a manner as to swing the deflector 7 about its pivot on the slightly down-turned end of the member 8.

15 While I have in this application specifically described one embodiment which my invention may assume in practice, it is to be understood that the form shown herein is used for purposes of illustration and that 20 the invention may be embodied in other forms without departing from its spirit.

What I claim as my invention, and desire to secure by Letters Patent, is:

1. In an ensilage delivery mechanism, 25 a delivery section, an adjustable section hingedly connected thereto and forming a continuation thereof, a sheave carried by said delivery section and having a threaded axial opening therein, a rod having a 30 threaded end received in the axial opening in said sheave and its opposite end thereof connected with said adjustable section, and means for rotating said sheave in opposite directions.

35 2. In an ensilage delivery mechanism, a delivery section curved upward and laterally, an adjustable section hingedly connected therewith and forming a continuation thereof, a sheave carried on said delivery 40 section and having a threaded axially disposed opening therein, a rod having a threaded end received in the axial opening in said sheave and its opposite end pivotally connected with said adjustable section, 45 and a rope engaging said sheave whereby it may be rotated in opposite directions.

Copies of this patent may be obtained for five cents each, by addressing the "Commissioner of Patents, Washington, D. C."

3. In an ensilage delivery mechanism, a delivery member having an upstanding delivery end, an ensilage deflector fitting the delivery end of said member and pivotally connected thereto, a bracket member carried on said delivery member, a sheave carried by said bracket and disposed transversely with respect to said delivery member, and a threaded member movable longitudinally by said sheave as the latter is rotated, having one end extending through said sheave and the other end pivotally connected to said deflector.

4. In an ensilage delivery mechanism, a 60 delivery member having a curved upper end, an ensilage deflector pivotally connected to the curved end of said delivery member and forming a continuation thereof, a bracket disposed laterally from said delivery member, a sheave rotatably mounted on said bracket and disposed transversely with respect to said delivery member and having a horizontally disposed threaded bore, an upstanding member carried on said deflector, 65 and a rod having an inclined end pivotally connected to said upstanding member and a horizontally disposed end threaded in the bore in said sheave.

5. In an ensilage delivery mechanism, a 75 delivery section curved upwardly and laterally, an adjustable section hingedly connected therewith, an upstanding bracket member secured to said adjustable section, a bracket member attached to the side of said 80 delivery section, a sheave carried on said last mentioned bracket having a threaded axial opening therein, a rod having a threaded end received in said axial opening and its opposite end pivotally connected to the bracket on said adjustable section, and a rope engaging said sheave whereby it may be rotated in opposite directions.

GEORGE M. MERWIN.
